UNITED STATES PATENT OFFICE.

FRANK W. GARRETT, OF NORWOOD, OHIO, ASSIGNOR TO THE BULLOCK ELECTRIC MANUFACTURING COMPANY, A CORPORATION OF OHIO.

BRUSH-HOLDER.

No. 848,120.

Specification of Letters Patent.

Patented April 3, 1907.

Application filed June 23, 1905. Serial No. 266,687.

To all whom it may concern:

Be it known that I, FRANK W. GARRETT, a citizen of the United States, residing at Norwood, in the county of Hamilton and State of Ohio, have invented certain new and useful Improvements in Brush-Holders, of which the following is a full, clear, and exact specification.

My present invention relates to improvements in brush-holders adapted for use in dynamo-electric machines.

In certain dynamo-electric machines, and particularly in railway-motors, it frequently happens that the commutator-surface becomes roughened or irregular to such an extent that if the brush-holders are not constructed to permit the brushes therein to respond readily to such irregularities there results considerable sparking at the brushes and chattering of same on the commutator.

The object of my invention is therefore to so construct and arrange the brush and holder as to permit the brush to respond readily to such irregularities as may exist in the commutator-surface, and thereby reduce to a considerable extent the sparking at said brushes and the noise due to the chattering of said brushes on the commutator.

In carrying out my invention I mount upon the top of the brush a yieldable or elastic member upon which the pressure-finger bears.

More specifically considered, my invention consists of the combination, with a brush-holder comprising a body and pressure-finger, of a brush carried by said holder, a clip mounted upon the upper end of said brush, and a spring-piece carried by said brush or clip, said pressure-finger resting upon said spring-piece.

In another aspect my invention consists of an article of manufacture comprising a brush-clip carrying a spring upon which is adapted to rest the pressure-finger of the brush-holder.

In the accompanying drawings, which illustrate the preferred embodiment of my invention, Figure 1 is a sectional elevation through part of a railway-motor, showing my improved brush-holder in its operative position. Fig. 2 is a plan view of the brush-holder shown in Fig. 1, and Fig. 3 is a detail elevation of the improved clip removed from the brush and holder.

Referring to said drawings, the motor-casing or field-magnet frame is indicated at 5 and the armature at 6. The casing supports the pole-pieces 7, carrying the field-coils 8. The armature is mounted upon the shaft 9 and carries the commutator 10. Fastened to the motor-casing is an insulating-block 11, upon which is adjustably mounted the brush-holder 12. Said brush-holder comprises the body 13 and the pressure-fingers 14, pivoted in said body at 15 and provided with springs 16 for forcing the brushes 17 into engagement with the commutator 10. The brushes 17 slide freely in the box-shaped guides 18, formed in said holder-body 13.

To permit the brushes to respond readily to the irregularities of the commutator, I provide U-shaped spring-pieces 19, which are located between the pressure-fingers and the brushes. Each of these spring-pieces is securely riveted or otherwise fastened to the spring-clip 20, which embraces the upper end of the brush 17. Rapid vibrations of the brush are taken up by this spring-piece without having same transmitted to the rigid pressure-finger 14. By this arrangement I gain the advantage of having a strong rigid pressure-finger rather than a weak resilient finger. I am also able to employ a simple article of manufacture in the form of a combined clip and spring which may readily be replaced if damaged. The U-shaped spring-piece 19 is here shown (see particularly Fig. 3) as having one leg fastened by rivets 21 to the top of the inverted-U-shaped spring-clip 20, with one end of a flexible conductor or shunt 22 firmly fastened between the spring-piece and clip. To produce a more rigid construction, I provide the filling-piece 23, through which the rivet or rivets 21 pass. The other end of each of said flexible shunts 22 is fastened to the brush-holder at 24. The shunt, clip, and spring-piece are readily removable from the brush and its holder in the condition shown in Fig. 3.

In the appended claims I aim to cover all modifications of my invention which do not involve a departure from its spirit and scope.

Having thus described my invention, what I claim as new, and desire to secure by Letters Patent, is—

1. In combination, a brush-holder comprising a body and a pressure-finger, a brush in said holder, and a yieldable member car-

ried by said brush and upon which said pressure-finger bears.

3. In combination, a brush-holder, comprising a body and a pressure-finger, a brush in said holder, and a yieldable spring-piece carried by said brush and upon which said pressure-finger rests.

3. In combination, a brush-holder, comprising a body and a pressure-finger, a brush in said holder, a clip mounted on the upper end of said brush, a spring-piece carried by said clip and upon which said pressure-finger rests, and a flexible conductor or shunt fastened to said clip and removable from said brush and holder with said clip.

4. In combination, a brush-holder comprising a body and a pressure-finger, a brush in said holder, a U-shaped spring-clip mounted on the upper end of said brush, and a spring-piece carried by said clip and located between the pressure-finger and said brush so as to permit the brush to respond readily to irregularities in the commutator of the machine.

5. As an article of manufacture, a brush-clip carrying a spring upon which is adapted

to rest the pressure-finger of the brush-holder.

6. As an article of manufacture, a brush-clip carrying a spring upon which is adapted to rest the pressure-finger of the brush-holder, and a flexible conductor or shunt fastened to said clip and spring.

7. As an article of manufacture, a brush-clip carrying a spring upon which is adapted to rest the pressure-finger of the brush-holder, and a flexible conductor or shunt having one end fastened to said clip and located between the clip and spring.

8. As an article of manufacture a U-shaped brush-clip having fastened thereto a U-shaped spring-piece upon which the pressure-finger of the brush-holder is adapted to rest when the brush and clip are in position in the brush-holder.

In testimony whereof I affix my signature in the presence of two witnesses.

FRANK W. GARRETT.
